UNITED STATES PATENT OFFICE.

EULABEE DIX BECKER, OF NEW YORK, N. Y.

EMBROIDERY AND PROCESS.

Application filed August 27, 1924. Serial No. 734,417.

This invention relates to a novel form of ornamentation and a method or process of producing the same.

It is an object of the invention to provide ornamentation, particularly as applied to material which may be used in connection with dresses, draperies, pillow covers, etc., and by means of which a novel and pleasingly artistic effect will be achieved.

Another object is to be predicated on the provision of novel ornamentation and a method of furnishing the same whereby effects in harmony with the individuality of the user may be produced with facility.

A still further object is that of providing an invention of the character stated, by means of which a surface to be ornamented may have this ornamentation applied to it far more quickly than has heretofore been practicable in applying embroidery and similar ornamental work to surfaces.

Another object is that of furnishing ornamentation and a method of producing the same, by means of which it will be feasible to utilize materials heretofore regarded as impracticable for this class of work, and further, in that materials of this nature may be employed to produce novel and striking effects.

Still another object is that of furnishing novel ornamentation which will not be injured or rendered unsightly despite severe usage.

Other objects of the invention will in part be obvious and will in part appear herein-after.

The invention accordingly comprises the several steps and the relation and order of one or more of such steps with respect to each of the others, and the article possessing the features, properties, and the relation of elements, which are exemplified in the following detailed disclosure and the scope of the application of which will be indicated in the claims.

For a fuller understanding of the nature and objects of the invention reference should be had to the following detailed descrip-

tion taken in connection with the accompanying drawing, in which:

Fig. 1 illustrates a strip of material which is suitable for use in practicing the process of ornamenting hereinafter particularly described;

Fig. 2 is a face view of a sheet of material and showing generally the ornamental effect produced;

Fig. 3 is a fragmentary enlarged view of a portion of the ornamentation as illustrated in Fig. 2; and

Fig. 4 is a transverse sectional view taken on the lines 4—4 in the direction of the arrows in Fig. 3.

It is to be understood that, for the sake of simplicity, and to enable those skilled in the art to readily follow the present invention, all of the foregoing views are of a somewhat diagrammatic nature. In actual practice the design will usually be of a far more complex nature than that illustrated in Figs. 2 to 4, and the strip or strips utilized in producing this design will ordinarily be of contrasting colors, which may or may not be harmonious with the background or base with which they are associated, and these strips themselves may carry figured designs in order to furnish a finished result which will be of an extremely artistic and pleasing nature.

While the ornamentation process forming the subject matter of the present invention may be practiced on backgrounds or mountings of material of any desired character, the same is particularly intended to be utilized in connection with goods which will not readily rip or unravel. For example, as in Figs. 2 and 4, in which the mounting portion has been indicated by the reference numeral 5, this material may be in the nature of linen, silk, knitted and woven fabrics, etc. Likewise, the embroidery element, i. e., the strip shown, for example, in Fig. 1, and identified by reference numeral 6, may be of any desired material, although it is preferred that the same be of such a nature that it shall be capable of presenting a frayed

edge, the threads of which are conveniently soft and of a fine texture.

The design to be produced may or may not be previously laid out upon the material 5, and according to the texture of this material a stiletto will or will not be employed in order to produce openings through which the strip may be subsequently threaded. It is to be borne in mind that in the instance of knitted fabrics being used, which are of a relatively porous or coarse nature, the openings may simply be formed by crowding certain of the threads aside, this being done by the needle or other implement 15 which carries the end of the embroidery element. However, in certain instances, where there exists the danger of the fabric 5 being torn, a suitable implement can be employed to provide the opening aforesaid.

A strip, as in Fig. 1, is torn or cut from a sheet of fabric, it being understood that the latter is chosen with the thought in mind that the component portions of the finished 25 design are to so blend with each other and with the background or base upon which they are mounted that a pleasing effect will be achieved. It is preferred that prior to the application of the strip 6 to the material 5 certain of the threads which constitute the 30 longitudinal warp thereof be removed from the parts adjacent the side edges of the strip, so that a frayed edge 7 is presented, the depth of which should be such that most 35 pleasing results will be obtained. If necessary, a stitching member, such as a needle with a large eye, may now be affixed to one end of the strip, and the latter is stitched through the body of the material 5.

Reference being particularly invited to Figs. 2 to 4, it will be noted in this fraying that that portion of the strip which lies adjacent to and beyond the outer face of the material 5 is preferably turned upon itself 45 as at 8 at points adjacent the loop ends which are threaded through the body of the material. These portions which are turned upon themselves may be flattened down by ironing so that the individual loops will not have a rumpled appearance in the finished 50 design, and by doing this any danger of the exposed design strips being too taut, and, consequently, presenting an unsightly appearance, will be avoided.

While numerous different methods of stitching may be employed, the foregoing is given as illustrative, and if this process is employed it will be noted, as in Figs. 3 and 4, that the strip may cross over underneath 60 the material 5, as at 9, so that each exposed stitch forms a unit of the complete design, and each hidden stitch (i. e., on the under-side of the material) provides a portion which bridges over to the next adjacent or 65 subsequent unit of the design.

Attention is also invited to the fact that, as nearly as possible, in making the designs a four to one ratio is maintained. In other words, the length of the stitch should preferably not exceed four times the width of the strip utilized, as otherwise it is found in most instances that certain of the longitudinal warp threads of the strip will become separated from the transverse threads, or else the exposed stitches will no longer be stable and retain their proper disposition relatively to each other. In connection with the frayed edges it is to be noted that by providing the same, and in addition to preventing a subsequently unsightly appearance of the design due to further fraying, the strips furnishing the thread will have an extremely soft outline.

From the foregoing it will be understood that the objects of this invention are achieved, and since certain changes in carrying out the above process, and certain modifications in the article which embody the invention may be made without departing from its scope, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which as a matter of language might be said to fall therebetween.

Having described my invention, what I claim as new and desire to secure by Letters Patent is:

1. In the art of producing embroidery, the method which includes the steps of tearing a strip from a piece of material longitudinally of certain of the threads thereof, fraying the edges of said strip, and stitching the same into a base with the stitches of such length that no further fraying of the edge will take place.

2. As an article of manufacture, ornamentation, including a base carrying a flat frayed strip stitched through openings formed therein, the diameters of said openings being less than the width of said strip and the length of the stitch being such as to prevent further fraying whereby the strip is of less effective width adjacent said openings.

3. As an article of manufacture, ornamentation, including a base carrying a frayed strip stitched through openings therein, the length of strip allowed for each stitch being such as to prevent further fraying and substantially greater than the distance between the openings provided for the ends of said stitch.

4. An artificial flower comprising a base

provided with perforations, a ribbon threaded through the perforations to provide loop portions on the upper side of the base.

5. An artificial flower comprising a base provided with perforations, a ribbon of a greater width than the perforations threaded therethrough to provide loose portions on the upper side of the base.

6. An artificial flower comprising a base provided with perforations, a strip of flexible material threaded through the perforations to provide portions on the upper side of the base which simulate the parts of a flower. 10

In testimony whereof I affix my signature.
EULABEE DIX BECKER.
